CLAIM

The ornamental design for a folding drying rack, as shown and described.

DESCRIPTION

FIG. 1 is an upper front perspective view of a folding drying rack showing the new design;

FIG. 2 is a lower rear perspective view of the folding drying rack of FIG. 1;

FIG. 3 is a front elevation view of the folding drying rack of FIG. 1;

FIG. 4 is a rear elevation view of the folding drying rack of FIG. 1;

FIG. 5 is a left side elevation view of the folding drying rack of FIG. 1;

FIG. 6 is a right side elevation view of the folding drying rack of FIG. 1;

FIG. 7 is a top plan view of the folding drying rack of FIG. 1;

FIG. 8 is a bottom plan view of the folding drying rack of FIG. 1; and,

FIG. 9 is an illustration of the claim in a use of environment of the folding drying rack of FIG. 1.

The broken lines (dash-dash) shown in the drawings illustrate portions of the article and form no part of the claimed design. Where no boundary line is shown between the solid and broken lines, it is to be understood a boundary line connects the ends of solid lines to demarcate a boundary between a claimed portion and an unclaimed portion. Dash-dot-dot-dash lines illustrate environment in which the design may be used, and form no part of the claimed design. Dash-dot-dot-dash lines and brackets indicate regions to be shown in discontinuous regions (e.g., interrupting otherwise continuous lines) and form no part of the claimed design.
